(54) **TANNING, BARK FOR**

(76) Inventor: **Daniel Williams**

Daniel Williams of Boston Mass.

Letters Patent.

The Schedule referred to in these Letters Patent and making part of the same containing a description in the words of the said Daniel Williams himself of his improvement in the process of preparing Bark and obtaining the extract therefrom

To all to whom these presents shall come.

Be it known that I Daniel Williams of Boston in the County of Suffolk and Commonwealth of Massachusetts have invented or discovered a new and useful improvement in the process of preparing bark and obtaining the extract therefrom for tanning for colouring and for other purposes, and that the following is a full and exact description thereof.

First. The hemlock oak or other bark from which the extract is to be made is divested of its outer part or rind either by shaving or cutting it off by hand or by the assistance of a machine constructed for the purpose.

Second. The inner part of the bark after being divested of the outer part or rind is cut into small pieces the tanning or colouring principle is then extracted from the bark so cut in pieces as aforesaid by leaching the same with hot water or by steam. From the liquor thus obtained the water is evaporated by boiling or by the sun and then the extract or gum is fit for use.

What I claim as my invention or improvement in the above described process of preparing the extract from bark and not previously known or used is the method of preparing the bark by cutting the same into pieces before leaching instead of pulverizing or grinding as has heretofore been practised or in other words preparing the extract from bark that

that is cut into pieces instead of from that which is ground or pulverised as has been heretofore practised. The advantages of this method over the common method of grinding or pulverising are that all the dust and minute particles which are produced by grinding or pulverising and which get into the extract prepared from pulverised bark and injure it are avoided and consequently the extract or gum which is obtained by the process above described possesses a clearness and purity which renders its value far greater than any which can be obtained by any previously discovered method.

In testimony that the above is a true specification of my said improvement as above described. I have hereunto set my hand this thirtieth day of November in the year of our Lord one thousand eight hundred and thirty five.
